UNITED STATES PATENT OFFICE.

SAMUEL WARD HAMILTON, OF CHICAGO, ILLINOIS.

DESIGN FOR A POULTRY-COOP.

43,277.

Specification for Design.

Patented Nov. 26, 1912.

Application filed June 28, 1912. Serial No. 706,497. Term of patent 7 years.

To all whom it may concern:

Be it known that I, SAMUEL WARD HAMILTON, a citizen of the United States, residing at Chicago, in the county of Cook and State of Illinois, have invented a new, original, and ornamental Design for Poultry-Coops, of which the following is a specification, reference being had to the accompanying drawing, wherein I have shown my new design.

Figure 1 is a plan view; and Fig. 2 is a side elevation.

I claim:

The ornamental design for a poultry coop, as shown.

SAMUEL WARD HAMILTON.

Witnesses:

W. LINN ALLEN,
MARY F. ALLEN.
